UNITED STATES PATENT OFFICE.

THOMAS G. MAXWELL, OF ALLIANCE, OHIO, ASSIGNOR, BY MESNE ASSIGNMENTS, TO THE McCASKEY REGISTER COMPANY, (INCORPORATED IN 1914,) OF ALLIANCE, OHIO, A CORPORATION OF OHIO.

FILING APPLIANCE.

1,141,401.

Specification of Letters Patent. Patented June 1, 1915.

Application filed December 17, 1908. Serial No. 468,005.

To all whom it may concern:

Be it known that I, THOMAS G. MAXWELL, a citizen of the United States, residing in Alliance, in the county of Stark and State 5 of Ohio, have invented certain new and useful Improvements in Filing Appliances, of which the following is a specification, reference being had therein to the accompanying drawings.

10 This invention relates to a filing appliance adapted for the systematic keeping of records, such for example as a merchant's credit accounts.

15 It particularly relates to the type of appliance shown and described in Patent No. 870,594, issued to Staples & Potter, November 12, 1907.

20 One object of the invention is to simplify the construction of apparatus of this character and to improve the manner of mounting the bill holding leaves.

25 Another object of the invention is to improve the shape and arrangement of the springs for counterbalancing the leaves.

30 Another object of the invention is to provide a series of pivotally supported leaves secured together by means which permit them to move laterally, whereby they are held in compact arrangement for storing in a safe or vault, such means being arranged to lie within the outside dimensions or space occupied by the leaves and their 35 pivotal supporting means.

35 A further object of the invention is to construct the bases with insets to receive the device or devices which connect the bases together.

40 Further objects of the invention consist of the parts and combination of parts hereinafter described.

45 For the purpose of illustration, I have, in the accompanying drawings, shown and herein described one form of filing appliance embodying my invention.

50 Referring to the drawings—Figure 1 is a side elevation of an appliance embodying my invention, one side of the cabinet being removed. Fig. 2 is a front view of the bill holding leaves removed from the casing, the upper portion of the leaves being broken away. Fig. 3 is a bottom plan view of the leaves. Fig. 4 is a fragmentary view of one end of a leaf and its supporting and counterbalancing means. Fig. 5 is a vertical

section through a portion of a leaf. Fig. 6 55 is a sectional view on the line 6—6, Fig. 5. Fig. 7 is a perspective view of a leaf pivot block, detached. Fig. 8 is a perspective view of a portion of a leaf showing a rubbing strip. 60

In the drawings, 1 indicates a casing or housing of any suitable or preferable construction. It may consist, as shown, of a bottom portion 2 having front and side pieces 2', 2'', respectively, a back 3, and a 65 hinged desk or lid 4.

5 indicates a platform adapted to support a pair of rests or uprights 6, preferably near opposite ends of the platform 5. The upper surface of each rest is preferably inclined and formed with a series of recesses 6'.

7, 7, indicate a series of bill holding leaves, and 8, 8, indicate a series of base bars to each of which is pivoted a leaf 7. 75 Each leaf 7 preferably consists of a sheet of thin metal, to the opposite faces of which spring bill clips 9 are secured. 10, 10, indicate strips arranged along the two sides or edges of each leaf. These strips, besides 80 acting as separators for the leaves, give strength and stiffness thereto, whereby they may be readily moved on their pivots from a substantially vertical to a substantially horizontal position. 85

12, 12, indicate a series of thin metallic strips extending from top to bottom on the opposite faces of each leaf. These strips are spaced apart to form pockets or compartments for the bills or other records to 90 be held by the clips 9. Each strip 12 is preferably bent into substantially U-shape to receive and hold a rubbing bar 13. The bar-holding strips 12 are preferably arranged in the same corresponding position 95 on both faces of each leaf so that a single rivet or set of rivets may be employed to secure two aligned strips to the leaf on its opposite faces.

The pivot connection between each leaf 7 100 and its base bar 8 preferably consists of an ear or lug 8' secured to, or formed integral with, the opposite ends of each base bar, a pin 8^a supported by the ear 8', and a pivot block 7^a. This block 7^a is provided with an 105 apertured projection 7^b which is rotatable on the pin 8^a. The blocks 7^a may be secured to the leaf in any suitable manner. I have

shown each as vertically slotted at 7^e to receive a corner of one of the sheet metal leaves and secured in position by rivets 7^a.

To counterbalance each leaf, I interpose 5 between it and its base bar springs 14, each preferably coiled around one of the pins 8^a. One end, 14', of each spring engages with the adjacent base 8, and its opposite end, 14'', extends upward and engages one face 10 of the adjacent leaf 7. Each base 8 is preferably formed with a recess 15 to receive the end 14' of the spring 14.

In order to permit the leaf engaging end 14'' of each coiled spring 14 to engage with 15 the front face of the leaf 7, the latter is formed with an elongated recess or depression 7^e to receive the said end 14'' of the 20 spring. As shown in the drawings, the opposite ends of each spring 14 extend tangentially from the said spring, that is the 25 said ends are not kinked or angularly bent at the point where they leave the coil, but extend off therefrom tangentially. By avoiding angular bends or kinks in the ends 30 of the springs the durability of the springs is increased and their life greatly lengthened. The springs 14 are preferably arranged so that when the leaf in normal use is inclined from its normal vertical position, 35 the resistance of the spring to being further wound up is utilized to return the leaf to normal position; but it is obvious that the spring could be arranged to operate, whereby its resistance to being unwound would be 40 utilized for similarly counterbalancing the leaf, without departing from the spirit of the invention.

15', 15', indicate a pair of lazy tongs connecting the bases together. These connecting devices permit the leaves to move laterally relatively to each other and be spaced 45 equally apart when placed in the casing, or closed together in compact arrangement when removed to store in a safe or vault.

45 16, 16, indicate a pair of slotted guides, each secured at one end to the outermost bases 8.

17 indicates a pin carried by each of the bases between the center and two outer bases 50 of the series and arranged to slide in the slot of an adjacent guide. These pins engaging with the walls of the adjacent slot, operate to prevent endwise movement of the bases relative to each other. The pins 55 17' of the central base 8^c are preferably somewhat longer than the pins 17, and are provided with screw threads, as shown at 17^a to receive set screws 17^b, whereby the bases may be secured in spaced or closed 60 position. The guides are preferably ar-

ranged side by side so that they have sliding engagement with each other and also assist in preventing relative endwise movement of the bases 8.

In order that the connecting and guiding 65 devices between the bases 8 will not occupy more space than that required by the leaves 7 and their connected bases 8, each of the latter is formed with an in-set section 8^d. By providing each base with an in-set 8^d 70 and connecting the lazy tongs and guides to these in-set sections, it will be seen that the space below the leaves and between the opposite pivot devices is utilized for the base bar connecting and guiding devices. By this 75 arrangement, the base connecting and guiding devices do not project beyond nor occupy more space than is actually required for the series of bases and pivoted leaves. This construction not only permits the storing 80 of a series of leaves in a minimum amount of space, but also permits the leaves to be stored in an upright position, so that the bills or records behind the spring clips 9 will not be displaced.

To those skilled in the art of making filing appliances of the class described, many alterations in construction and widely different embodiments and applications of my invention will suggest themselves, without departing from the spirit and scope thereof. My disclosures and the description herein are purely illustrative, and are not intended to be in any sense limited.

What I claim is—

1. In an account appliance, the combination of a slip holding leaf or frame, U-shaped strips secured thereto to form pockets on the said leaf or frame and means for securing slips upon the said leaf or frame. 100

2. In an account appliance, the combination of a pivotally mounted bill holding leaf, U-shaped strips secured thereto to form pockets on the said leaf, and a rubbing bar supported by each of said strips. 105

3. In a filing appliance, the combination of a bill holding leaf adapted to swing from one position to another, a U-shaped strip secured to said leaf to form a pocket, and a rubbing bar arranged in said pocket, the 110 side members of said strip terminating in a plane co-incident with the face of said bar.

In testimony whereof I affix my signature, in the presence of two witnesses.

THOMAS G. MAXWELL.
